Specification for Design.

Patented Jan. 23, 1917.

Application filed November 3, 1916. Serial No. 129,401. Term of patent 3½ years.

To all whom it may concern:

Be it known that I, GUSTAVE M. FAUSER, a citizen of the United States, residing in the city of New York, county of New York, and State of New York, have invented a new, original, and ornamental Design for a Border for Wall-Paper; and I hereby declare the following to be a description of the same in such terms as will enable any one skilled in the art to which it appertains to make and use the same, reference being had to the accompanying drawings.

Copies of this patent may be obtained for five cents each, by addressing the "Commissioner of Patents, Washington, D. C."

The figure of the drawing is a plan view of a section of wall paper border illustrating my new design.

The design as shown is intended to be repeated or matched out upon either side indefinitely as is usual in such cases.

What I claim is:—

The ornamental design for a border for wall paper as shown and described.

GUSTAVE M. FAUSER.
